VOLTAGE REGULATION

Joseph W. Allen, East Orange, N. J., assignor to
 Bendix Aviation Corporation, South Bend, Ind.,
 a corporation of Delaware

Application August 26, 1941, Serial No. 408,375

2 Claims. (Cl. 201—51)

This invention relates to voltage regulation, and particularly to the regulation of generator voltage by control of the resistance to current flow in a component part of the generator assembly, such as the shunt field circuit.

The use of carbon pile or equivalent pressure responsive resistors to control current strength is old in the art. It is also old to provide switch mechanism for short-circuiting such resistors, in order to eliminate entirely one or more sections of such resistance; for even after said sections have been compressed the maximum amount, there is still more or less resistance to current flow therethrough.

Such short-circuiting devices as have been suggested heretofore have not been satisfactory for, one reason or another; a principal difficulty being due to the lack of sufficient sensitivity to slight pressure increments in either direction. Because of this lack of sufficient sensitivity the complete elimination of all resistance would not occur with the degree of promptness necessary to secure good regulation. To provide a more sensitive, hence a more accurately responsive, short-circuiting switch mechanism in a device of the character indicated, is an object of the present invention.

Another object of the present invention is to provide in a carbon-pile regulator, novel means for combining switch mechanism therewith, in such manner that both are subject to the same operating forces.

A further object is to provide novel operating means for a carbon-pile regulator.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing:

Fig. 1 is a longitudinal sectional view of a device embodying the invention;

Fig. 2 is a transverse view along line 2—2 of Fig. 1; and

Fig. 3 is a diagram of the electrical connections.

In Fig. 3 numeral 5 designates a generator having a shunt field 6 across the mains 7 and 8 of which is bridged a battery 9. Serially connected in the shunt field circuit is the variable

resistance unit 11 in the form of a pile of carbon discs 26 stacked in a retaining capsule 23 (see Fig. 1) that is mounted in a metallic spool 13 provided with heat radiating (cooling) fins 16, separated one from the other by spacer rings 12. A nut 17 threadedly engages the threaded end 18 of the spool 13, and serves to adjustably clamp the spacers 12 and fins 16 against the shoulder 19 of the spool; a second shoulder 21 facilitating staking of the spool to the supporting plate 22. The insulating capsule 23 is interposed between the spool 13 and the carbon stack 26, and current is fed to the carbon stack by way of terminal plug 29 threaded into the hub 31 of the retainer ring 32. Plate 22 is insulated from ring 32, as shown at 34 and 35; apertures 36 being provided to receive retaining screws or bolts (not shown). A solenoid is provided, and includes a magnetic core 41 fixed to a magnetic housing 42 (as indicated at 43), a winding 44 on said core, and an armature 46 movable with respect to the core 41, to engage magnetic flange 47 of the housing 42 when the winding 44 is energized, and to be disengaged therefrom by the action of resilient members 51 when the winding 44 is de-energized. Members 51 are secured to the armature assembly by screws 52, as indicated.

The novel means for transmitting the movement of solenoid armature 46 to the carbon stack 26 will now be described. A coupling element 61, whose flange 61' is secured to the armature assembly by screws 52, is slidably received within a second coupling element 63, and a "dished washer" type of annular spring is interposed between flat surfaces on said coupling elements, as indicated at 64. Coupling element 63 is threaded into a yoke 66, and coupling element 61 is counter-bored to receive a current conducting contact screw 68 and a sleeve 67 of insulating material. A second contact screw 69 is carried by a plate 71 which is in turn carried by yoke 66, and a second plate 74 is carried by said yoke and serves to connect the yoke to a swivel coupling element 73 whose co-operating element 76 has operative connection with the end portion 18 of spool 13. A nut 81 allows adjustment of the gap between coupling elements 61 and 63, and hence controls the setting (initial stress) of spring 64.

From the foregoing it will be apparent that the position of the armature 46 with respect to the stationary magnetic elements 41 and 47 will depend upon the strength of the magnetic field built up by the current flowing through the

winding 44, and thus in turn will depend upon the prevailing voltage across the mains 7, 8 of the generator circuit. When the voltage tends to rise above the normal value, the magnetic field will be increased sufficiently to draw the armature into actual abutment with the magnetic pieces 41 and 47 (this being the position indicated in Fig. 1) and in this position the springs 51 are fully stressed and the pressure upon the carbon stack 26 is at the minimum due to the fact that the actuating assembly including the parts 63, 66, 74 and 73 are now in their extreme left-hand position, as viewed in Fig. 1, and therefore they apply a minimum of pressure to the carbon stacks. The result is that the resistance to current flow through the carbon elements is at a maximum, and therefore the tendency is for the field current to be reduced in strength thereby tending to reduce the speed of the generator and thus restore the voltage across the mains 7, 8 to normal. As this restoration takes place the resultant decrease in voltage across the winding 44 and the consequent weakening of the magnetic field permits the springs 51 to assert themselves, thus tending to shift the assembly including the parts 61', 64, 63, 66, 74 and 33 to the right—all these parts moving as a unit, and with no substantial relative movement as between the parts 61' and 63 during the initial stages of this rightward movement. However, when the resulting compression of the carbon stack proceeds sufficiently to present substantial resistance to further rightward movement of the assembly, the stress in the spring 64 builds up and finally there is a snap action of said member 64, at which time the springs 51 become effective to follow up the snap action of the spring 64 by a sharp rightward movement of the member 61; and as the member 61 thus moves to the right to shift its position in relation to the resisted 40

member 63, there is a positive closing of the circuit to the contacts 68 and 69 and the resulting short circuiting of the carbon stack 26. This action eliminates any residual resistance remaining in the carbon stack and thus increases the current flow through the shunt field 16 sufficiently to accelerate the generator to the extent necessary to maintain normal speed and voltage output. When the speed and output again rises above normal, the cycle is repeated and thus regulation is maintained.

What is claimed is:

1. In a regulator of the carbon pile type, for regulation of generator voltage, a pair of relatively movable switch members in shunt with the carbon pile, means for preventing relative movement of said switch members upon generator voltage fluctuations of relatively slight magnitude, said preventing means including an electromagnetic armature assembly responsive to voltage fluctuations, means positively connecting said armature assembly with one of said switch members, and lost-motion means connecting said armature assembly with the other of said switch members.
- 15 2. In a regulator of the carbon pile type, for regulation of generator voltage, a pair of relatively movable switch members in shunt with the carbon pile, means for preventing relative movement of said switch members upon generator voltage fluctuations of relatively slight magnitude, said preventing means including an electromagnetic armature assembly responsive to voltage fluctuations, means positively connecting said armature assembly with one of said switch members, and snap action means connecting said armature assembly with the other of said switch members.

JOSEPH W. ALLEN.
